WITNESS:

William E. Lloyd

INVENTOR

Victor J. Evans

ATTORNEY

UNITED STATES PATENT OFFICE.

WILLIAM E. LLOYD, OF LORAIN, OHIO.

BUSHING EXTRACTOR.

Application filed August 31, 1922. Serial No. 585,469.

To all whom it may concern:

Be it known that I, WILLIAM E. LLOYD, a citizen of the United States, residing at Lorain, in the county of Lorain and State of Ohio, have invented new and useful Improvements in Bushing Extractors, of which the following is a specification.

This invention relates to tools, particularly to extractors, and has for its object 10 the provision of a novel device for extracting bushings from machine elements.

An important and more specific object is the provision of a tool of this character which is expansible whereby to exert the 15 necessary gripping action against the inner walls of bushings of different sizes.

An additional object is the provision of a device of this character which will be simple and inexpensive in manufacture, easy to 20 operate, efficient and durable in service and a general improvement in the art.

With the above and other objects and advantages in view the invention consists in the details of construction to be hereinafter 25 more fully described and claimed and illustrated in the accompanying drawings, in which:

Figure 1 is a side elevation of the device,

Figure 2 is a longitudinal section showing 30 it in use,

Figure 3 is a cross section on the line 3—3 of Figure 1, and

Figure 4 is a cross section on the line 4—4 35 of Figure 1.

Referring more particularly to the drawings the letter A designates a portion of a machine element within which is a bushing B to be extracted. In carrying out my invention I provide an elongated shank 10 formed at one end with a head 11 and having its other end threaded as shown at 12. Slidably mounted upon this shank is a sleeve 13 having a conical head 14 co-operating with a plurality of tapering externally 40 toothed sectional jaws 15 which are formed with reduced extensions 16 adjacent which are grooves 17 which receive a coil spring ring 18 which acts as a fulcrum or pivot. The sleeve 13 is operated by means of a nut 19 screwed upon the threaded end of the shank.

The device further includes a cross member or brace 20 which is slidably passed over the threaded end 12 of the shank and which is designed to have blocks of wood C inserted between it and the machine element from

which the bushing is to be extracted. I also provide a second nut 21 screwed onto the threaded end of the shank and engaging the cross member or brace 20. In the operation 60 of the device, the nut 19 is retracted so that the sectional toothed jaws 15 will be in contracted position. The jaws are then inserted into the bushing B as shown in Figure 2 and the nut 19 is turned down to cause the sleeve 13 to move longitudinally toward the head 11. The engagement of the conical head 14 with the free ends of the jaws will cause them to expand, their toothed outer portions biting into the inner wall of the 70 bushing and effectually gripping the same. The blocks of wood C are then laid on the machine element A, the cross member or brace 20 is slipped on to the shank and engaged upon the blocks and the nut 21 is then 75 applied and turned down. This movement of the nut 21 will operate to draw the shank longitudinally, carrying with it all the associated parts and effecting extraction of the bushing in an obvious manner.

From the foregoing description and a study of the drawings it will be apparent that I have thus provided a simply constructed and consequently inexpensive tool which will be a great time and labor saver 80 in removing bushings. Owing to the simplicity of the construction and the fewness of the parts it is apparent that there is nothing to get out of order so that the device should have a long life and satisfactorily 85 perform all of its functions.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. A tool of the character described comprising an elongated shank terminating at one end in a head and threaded throughout its major portion, a plurality of jaws pivoted on said shank and having toothed outer faces, a sleeve slidably along the shank and terminating at one end in a conical head engaging between the free ends of the jaws, a nut threaded onto the shank and engaging said sleeve for effecting longitudinal movement thereof to expand the jaws, and screw means for moving the shank lengthwise.

2. A tool of the character described comprising an elongated shank terminating at one end in a head and threaded throughout its major portion, a plurality of jaws pivoted on said shank and having toothed outer faces, a sleeve slidable along the shank and terminating at one end in a conical head engaging between the free ends of the jaws, a nut threaded onto the shank and engaging said sleeve for effecting longitudinal movement thereof to expand the jaws, and screw means for moving the shank lengthwise, consisting of a cross member slidably engaged upon the shank and adapted to rest upon supporting blocks laid upon the element containing the bushing to be extracted and a second nut screwed onto the shank and engaging said cross member. 30
3. A bushing extractor comprising a shank having one end threaded and its other end carrying a head, a plurality of jaws disposed against the shank and formed with reduced extensions and grooves, the outer faces of the jaws being toothed, a coil spring ring encircling the jaws and fitting within said grooves to constitute a pivot, a sleeve slidable on the shank and carrying a conical head engaging within the free ends of the jaws, a nut screwed on the shank and engaging the sleeve for moving the same lengthwise, a support carried by the shank and engageable with stationary elements laid against the element containing the bushing to be extracted and screw means for moving the shank longitudinally with respect to 35 said support. 40
4. A tool of the character described comprising an elongated shank threaded throughout its major portion, a plurality of jaws pivoted on said shank and having their outer surfaces curved and toothed, means slidable along the shank and engaging said jaws for effecting expansion thereof and a nut member threaded onto the shank for moving said member. 45
5. A tool of the character described comprising an elongated shank terminating at one end in a head having a concaved surface, a plurality of jaws having curved ends rockably mounted within said concaved surface, a circular spring surrounding the jaws and holding them in position, and a wedge member movable along the shank and engageable with the jaws for expanding the same. 50

In testimony whereof I affix my signature.

WILLIAM E. LLOYD.
